(57) **CLAIM**

The ornamental design for a side air intake assembly, as shown and described.

DESCRIPTION

FIG. 1 is an environmental perspective view of a side air intake assembly showing our new design for one side of a vehicle;

FIG. 2 is a perspective view of the side air intake assembly of FIG. 1 without the environmental elements;

FIG. 3 is a right side view of the side air intake assembly shown in FIG. 2;

FIG. 4 is a top view of the side air intake assembly shown in FIG. 2;

FIG. 5 is a bottom view of the side air intake assembly shown in FIG. 2;

FIG. 6 is a front view of the side air intake assembly shown in FIG. 2;

FIG. 7 is a rear view of the side air intake assembly shown in FIG. 2;

FIG. 8 is an environmental perspective view of a side air intake assembly showing our new design for the other side of the vehicle;

FIG. 9 is a perspective view of the side air intake assembly of FIG. 8 without the environmental elements;

FIG. 10 is a left side view of the side air intake assembly shown in FIG. 9;

FIG. 11 is a top view of the side air intake assembly shown in FIG. 9;

FIG. 12 is a bottom view of the side air intake assembly shown in FIG. 9;

FIG. 13 is a front view of the side air intake assembly shown in FIG. 9; and,

FIG. 14 is a rear view of the side air intake assembly shown in FIG. 9.

The broken lines shown in the figures represent portions of the side air intake assembly that form no part of the claimed design.

1 Claim, 12 Drawing Sheets
